UNITED STATES PATENT OFFICE.

LAWRENCE A. HOFSTETTER, OF UNION CITY, NEW JERSEY.

LAMP-SOCKET CONSTRUCTION.

Application filed April 14, 1926. Serial No. 102,024.

This invention relates to a construction of lamp socket.

An object of the invention is to provide a simple and efficient lamp socket, especially 5 adapted for Christmas tree lamps whereby when any one of a plurality of lamps in series has its filament broken, the broken lamp can be quickly discovered.

A further object is to provide a lamp construction for this apparatus which is simple, 10 efficient, durable, economical to manufacture and composed of a minimum number of parts.

The invention is illustrated in the drawings, of which—

Figure 1 is a side elevation of a pair of lamps in circuit with the new and improved form of socket;

Figure 2 is a section through the socket 20 with a lamp disposed therein.

The form of the invention shown in the drawings is a preferred form, although it is understood that modifications in the construction and arrangement of the parts and 25 in the character of the materials used may be adopted without departing from the spirit of the invention as set forth in the appended claims.

In its general aspect the invention comprises 30 a socket for a lamp which is resiliently mounted and provided with means whereby the filament is placed in circuit when the socket is disposed in one position and whereby the filament is short circuited 35 when the socket is moved to another position. This general effect is achieved by mounting the socket within a casing on a resilient cushion which holds it in an elevated position. The connections to the 40 socket in this position are such that the filament is placed in circuit. When however, the socket is disposed against the action of the cushion contacts are made which short circuit the filament.

In this manner and with this construction 45 if a plurality of lamps are disposed in a series circuit and are each provided with sockets of this kind, whenever one of them blows out at its filament, the lamp with the 50 broken filament may be discovered merely by successively depressing each lamp in its socket until that lamp, which when depressed will cause the balance of the circuit to be illuminated. This illumination with the 55 lamp thus depressed is the one with the broken filament.

In the preferred form of the invention I show a lamp having a bulb 10, a base shell 11 and a central base contact 12. This lamp is adapted to be screwed into a socket 13 which is of the usual type, only in this case it is supported within the casing 14 on a resilient cushion such as a spring 15 held beneath oppositely extending pins 16 and 17 formed on the socket. These pins slide 60 in slots 18 and 19 in the casing 14. In the bottom of the socket 13 is an insulating washer 20 which supports a contact disc 21 from which a conducting stem 22 projects through an opening 23 in the bottom of the 70 socket. Wire 24 is connected to this stem 22 and passes through an insulating sleeve 25 disposed in the bottom of the casing 14. Wire 26 is connected to a conducting disk 27 which is disposed in the bottom of the 75 casing, the casing 14 being of insulating material.

As shown in Figure 2, when the lamp is screwed into the socket and is in the position shown, the circuit would be as follows:— 80 from wire 24, stem 22, contact disc 21, contact 12 on the base of the lamp through the filament of the lamp to the recess 11, thence to the socket 13 through the spring 15 to the disk 27 to the wire 26. When the lamp is 85 depressed against the action of spring 15 the stem 22 will contact with the disk 27 and thereby directly connect wires 24 and 26, thus short-circuiting the filament of the lamp. Therefore if this lamp is one with a broken 90 filament in series with a plurality of others which are unbroken, then the depression of this lamp will re-establish the circuit by short-circuiting this broken filament and immediately indicate the lamp which needs 95 replacement.

What I claim is:

1. A lamp socket which comprises a 100 socket to receive a lamp base, a casing in which the socket is movably mounted, resilient means for supporting the socket in the casing and holding it in normal position, means for placing the lamp filament in circuit when the socket is held in normal position in the casing, and means for short-circuiting the filament when the socket is moved against the action of the resilient means.

2. A lamp socket, comprising a casing, a 110 socket to receive a lamp base having sliding and guided movement in the casing, a spring in the casing and holding the socket in outward position, means for placing the lamp

filament in circuit when the socket is held in outward position by the spring, and means for short-circuiting the filament when the socket is slid in the casing against the 5 action of the spring.

3. In combination with a lamp socket, a casing in which said socket is disposed, a resilient cushion supporting the socket within the casing, a conducting disk within the 10 casing, circuit connections to the disk, circuit connections to the central terminal of a lamp disposed in the socket, connections between the shell of the lamp and the socket, connections between the socket and the disk 15 and means whereby when the socket is depressed against the action of the cushion the central contact of the lamp is brought in contact with the disk.

4. In combination a casing, a socket there-

in, a coil spring resiliently supporting said 20 socket in an elevated position, a conducting disk in the bottom of the casing, a lamp base adapted to be screwed into said socket, said socket having an opening in the bottom thereof, an insulating washer within the 25 socket around said opening, a contact disc supported on said washer, a dependent conducting stem connected to the disc and projecting through said opening, said disc adapted to make contact with the central 30 base contact of a lamp disposed in the socket, a wire connected to the conducting stem and insulated from the casing, a wire connected to the disk in the bottom of the casing, said 35 stem and disk adapted to be brought in contact when the socket is depressed.
